UNITED STATES PATENT OFFICE.

GEORGE C. WERNER, OF BEATRICE, NEBRASKA.

COUNTERBALANCING DEVICE FOR PUMPS.

No. 890,477.

Specification of Letters Patent.

Patented June 9, 1908.

Application filed May 14, 1907. Serial No. 373,550.

To all whom it may concern:

Be it known that I, GEORGE C. WERNER, a citizen of the United States, residing at Beatrice, in the county of Gage and State of Nebraska, have invented a new and useful Counterbalancing Device for Pumps, of which the following is a specification.

This invention relates to counterbalancing devices for pumps and has for its principal object to provide a novel form of cushioning return spring for equalizing the operation of the pump and preventing damage from unnecessary jar where the device is employed in connection with a wind mill or similar operating means.

A further object of the invention is to relieve the wind mill of all strain in the working of the pump, and to so arrange the structure that a supply of water can be had when a very light or fitful wind is blowing.

A still further object is to provide an improved mounting for the springs, and to employ springs which will permit full range of stroke.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a sectional elevation of a pump attachment constructed in accordance with the invention. Fig. 2 is a plan view of the same, partly in section. Fig. 3 is a detail perspective view of one of the springs and its connections.

Similar numerals of reference are employed to indicate corresponding parts throughout the several figures of the drawings.

In carrying out the invention, two plates 10 and 11 are placed over the piston rod, these plates being provided with openings which will accommodate a rod of cylindrical or flat form in cross section. The lower plate 10 rests on and may be bolted to the pump head while the upper plate is suitably secured to the piston rod.

Secured to and extending upward from the lower plate 10 are a number of vertically dis-

posed posts 15, three of which are shown in the present instance, these posts passing through guiding openings formed in the upper plate 11 and serving as supports for helical springs 16 which in practice will lift about twenty per cent. of the weight of the piston, piston rod, and column of water, and the springs are of sufficient length to accommodate the full stroke of the pump.

At suitable intervals the upper and lower plates are connected by suitable springs 20, each spring being preferably formed of spring wire centrally bent to form a loop 21, and thence extended outward, the two arms 70 of the spring being coiled, and the arms thence turning at an angle to the former bend to the point where they are to be fastened to the upper plate 11, and at the upper ends are turned to form flat hooks 22, the extreme 75 ends of the hooks being bent into parallel relation with the arms. The lower loop 21 passes through an eye formed in a keeper 25 that is held in place against the lower plate 10 by one of the hooks 15, the latter passing 80 through an opening that is formed in the keeper, and said keeper is further confined by means of a suitable clamping bolt 27. The upper hooked ends of the spring are secured in place by pivoted clips 30 which are connected to the upper plate 11 by means of bolts 31, the bolts forming pivots on which said clips may swing in order to accommodate the variation in angle of the springs when the latter are compressed and expanded.

One of the principal difficulties experienced in pump attachments of this nature is that the springs are either rigidly confined to the carrying plates and thus break at the point of connection, or are so loosely confined that they become displaced during heavy and rapid work. In the present instance the springs are provided with hinged connections of such nature that there is no bending strain on the springs at the points where they are attached to the plates, there being sufficient freedom of movement to accommodate the slight variations in angle of the springs during the stroke of the piston.

It is preferred in practice to employ a spring cushion which will lift a load of ten or fifteen per cent. more than the whole weight of the piston and the column of water, so that no strain will be imposed on the wind mill during the up stroke, and during the down stroke the springs will act to gradu-

ally cushion the movement of the plunger rod, and thus prevent the jar and noise incident to the operation of devices of this character as ordinarily constructed.

5 I claim:—

1. In a pump attachment of the class described, upper and lower plates, each provided with a centrally disposed opening for the passage of the plunger rod of the pump, 10 equi-distant vertically disposed standards carried by one of the plates, the other plate having equi-distantly spaced openings for the passage of said standards, helical springs surrounding the standards at points between 15 the plates, and a plurality of sets of equi-distantly spaced coiled springs having their terminal arms secured to the outer portions of said plates.

2. In a pump attachment of the class described, the combination with a pair of plates, 20 of a plurality of spaced standards carried by

one of said plates, the opposite plate having openings for the passage of said standards, coiled compression springs mounted on the standards between the plates, a series of 25 keepers having openings for the passage of the standards, securing bolts for the keepers, a double spring having a central loop passing through the keeper, said spring being bent to form a pair of spaced coils, the terminal 30 arms being bent to form flat hooks, and a pair of spaced pivoted clips carried by the other plate and to which said hooks are connected.

In testimony that I claim the foregoing as 35 my own, I have hereto affixed my signature in the presence of two witnesses.

GEORGE C. WERNER.
